CENTRIFUGAL PUMP

Charles M. Veach, Well's Tannery, Pa.

Application May 17, 1930, Serial No. 453,152

5 Claims. (Cl. 103—103)

Centrifugal pumps that have a non-positive output have a very wide range of utilization. They are used for lifting liquids, for ejecting liquids from a nozzle, into the atmosphere and sometimes against pressure, and very particularly for liquid transmission devices, and also for many other purposes to which the variable pressure produced by varying the rotor's speed makes them peculiarly applicable.

10 My pump, which may be used particularly well as an element of transmission devices, has a pressure chamber in which a large portion of the liquid handled by the pump is put under a pressure in an annular chamber circumferentially extending around the rotor by the rotor's revolution, but itself remains nonrotating. It is under varying pressure in proportion to the rapidity of the rotor's revolution and to the resistance to the liquid's passage from the pressure chamber. If 15 the outlet for the liquid held under pressure is closed, the rotor's turning is not stopped, and apparently is not interfered with substantially. The liquid in the pressure chamber remains at rest, and the liquid in the rotor remains in it, and, 20 where the rotor is slightly retarded by friction, there is no shock over the closing of the outlet from the pressure chamber, or its partial closing. This pressure in the pressure chamber varies 25 also with the freedom with which it is allowed to pass therefrom. Two main factors, therefore, 30 exist governing largely the amount of pressure in the pressure chamber and in the conductor leading from it, viz the rapidity of the rotor's revolution, and the freedom of the liquid's passage from 35 the pressure chamber. This latter is particularly important when the pump is used with a positively acting liquid driven rotary motor, the fluid pressure that causes the rotation of which will be increased if this rotary motor is slowed down 40 by an increased load, and therefore an increased load means an automatically increased power in the driven motor at a lesser speed of the motor, a result very useful in automobile transmission devices.

45 The power of the driven motor can also be increased, by increasing the speed of the rotor of the pump, without diminishing the motor's speed. The speed of the vehicle therefore can be completely regulated by a control of the supply of combustible material to the engine.

50 Describing now the best form of my device of which I am at present aware,

Fig. 1 is a side elevation of the pump with the plate nearer the observer removed, showing the 55 positions of the parts beneath it. Fig. 2 is a view partly in section on the line 2—2 of Fig. 1. In this view the rotor and its driving elements are not in section. Fig. 3 is a view fully in section on the same line.

60 The device has a chamber A, to contain the

liquid under pressure. This chamber is formed along the circumference of the casing 1, which latter may be formed of any convenient form of side plates or castings 2, with a rim, 3 to which the side plates 2 may be bolted by bolts, or otherwise suitably secured. The chamber A, lies adjacent to the rim 3, and between the side plates 2, 2. The boundary of the chamber A, toward the axis of the pump is a perforated screen 5. This screen extends between the sides of the pump, and, in practice, is annular. It may or may not be coaxial with the rotor, and may or may not be equally spaced from the rim, at all points in its circumference. These limitations of position are not necessary, since revolution of the fluid in the chamber A is not desired. This screen 5, serves to separate the chamber A from a space B, between the circumference 7, of the rotor and the screen 5, in which space the liquid rotates, at a rate a little less than the rate of rotation of the 10 rotor. The screen is, in practice, a ring of thin metal, pierced with a large number of small perforations. This space B, between the circumference of the rotor and the screen is narrow, as will be explained below. All the parts above 15 mentioned, except the rotor are stationary in practice, as there is no advantage in having them 20 rotate in the present form of my device.

The axis of revolution of the rotor may be horizontal or vertical. I have shown it as vertical with the corresponding position of the other parts of the device, but my invention is not limited to a rotor, or the other pump parts so placed.

30 The rotor 6 is constructed, as follows:—A series of radially extending conductors 9 are mounted on a rotating hub 14, and have outlet mouths a, a, a, a, adjacent to the screen 5. A narrow space is left between them and the inner surface of the screen 5 (the space B). These conductors 9, may be in the form of ordinary cylindrical pipes, as shown in the illustrations. The circumference of the rotor is closed between the mouths a, so that the friction caused by its contact with the liquid in the space B, is minimized. The rotor 35 has a ring 12, that is circular and closes the spaces between the mouths a, a, a, a, forming a continuous surface. The sides 13, of the rotor are flat, and may be formed of discs of sheet material suitably secured, as by brazing, to the ring 12. This construction of the rotor is a very advantageous 40 one, for the greater part of its weight is substantially that of the water contained in the conductors 9. The water so contained does not press outward against any part of the rotor. The circumferential ring 12 closing the spaces between 45 the outlets a, a, a, a, of the conductors 9 and the side pieces being brazed to it keep the water out of the spaces between the conductors 9, so that the rotor having the empty spaces is extraordinarily light for its size. The hub 14, rotates on 50 55 60

suitable bearings, very conveniently on roller bearings on a stationary support which may be a pipe 15, for the intake of the liquid handled by the pump. This construction provides air spaces 5 D in the rotor that will make it substantially lighter. The driving fluid will be contained only in the pipes that constitute the conductors 9, leaving all the rest of the space between the sides 13 and the ring 12 empty except for the air contained in it. The rotor is spaced so that the friction 10 retarding its revolution will be minimized, which with oil will not require that the side wall of the motor be more than an inch from the inside of the wall of the casing 1.

15 The driving mechanism for the rotor is placed, in practice, inside of the casing. In practice, I use a driving gear 17, the shaft 18 of which passes through a gland 19 that is mounted on the side 2 of the casing and may have an enlarged bearing 28 that bears on this side. The driven gear 20 is mounted on the rotor, in practice, on a hub 25 14. The rotor preferably revolves on a stationary pipe 15 which has apertures such as the holes 23 that allow the liquid to pass from the pipe 15 into the conductors 9. This liquid is prevented from 30 entering the space D, by suitably closing the space between the mouths that open into the space around the pipe 15.

An outlet 25 is provided for the exit of the liquid 35 from the chamber A. The valve 26 may be placed in it when the regulation or control of the outflow of liquid from the pump is desired. The gears 17 and 20 run in the liquid. If this liquid is oil, as it would usually be if the pump was part of a transmission system, the lubrication of these parts and 40 of the bearings of the rotor is assured.

The action of the pump is differentiated from other centrifugal pumps in several ways. The liquid in the chamber A, does not rotate substantially, but remains always under a heavy pressure 45 which is exerted radially by the liquid in the rotor, the pipes and the screen co-operating to produce this result. The liquid in the space B rotates, but its volume is small. The pump runs best entirely full of liquid, but it will operate when partly filled with but little diminished power.

The pressure in the chamber A is a function of 50 two variable quantities, the pressure of the liquid in it from the liquid in the rotor, and, to an extent, from the pressure of the liquid in the space B and the freedom with which the liquid can pass through the outlet 25. The precise fluctuation of the liquid through the perforations in the screen is not readily determinable. In practice, a steady 55 outward pressure is maintained in the chamber A. The outflow from this chamber has all the qualities of a stream having a fixed and very high head, as it is always possible to drive the rotor at a speed sufficient to produce this result if the proper proportional number of perforations of the parts is maintained. The outlet may be entirely free, which will be the case ordinarily when the problem is simply to raise water, or it may lead 60 into a motor which can be piston or turbine. An increased load on the motor will slow it down, checking the flow from the outlet from the chamber A and therefore increasing the pressure in it.

I have found that no appreciably greater load 65 is put on the engine driving the rotor, which latter continues at constant speed, so that the engine's speed remains constant when a resistance is encountered by the liquid pressing out from

the pump. This fact makes the pump particularly effective in driving any motor that varies in speed, and at lower speeds needs a greater liquid pressure to insure its operation. This gives automatically a greater driving power to the motor driven by my pump at the motor's lower speeds.

5 I do not limit myself to the particular mechanical pump structure described above. There are many ways in which a chamber pump containing a volume of liquid that is not substantially rotating, held under pressure by the revolution of a 10 rotor may be constructed so far as the casing, liquid feed and even the pressure chamber may be concerned, and these, provided they fall within a fair construction of my claims are included in 15 my invention.

I claim:—

1. In a centrifugal pump having a stationary pressure chamber with a perforated ring between which and the inner face of the outer walls of 20 the chamber a quantity of the liquid is held substantially without rotation and under heavy pressure, the rotor comprising in combination a series of radial pipes extending from a central intake, a circumferential ring enclosing the circumference of the rotor except at the mouth of the pipe and flat side pieces at each side of said rotor brazed to the edges of the circumferential ring thereby forming between the side pieces and the 25 circumferential ring enclosed air spaces. 30

2. A centrifugal pump comprising a stationary pressure chamber, with a perforated ring between which and the inner face of the outer circumferential walls of said chamber a quantity of the liquid is held substantially without rotation and under heavy pressure, and a rotor comprising in combination, a central inlet, a hub, a series of radially arranged pipes leading from the central inlet to the circumference of the rotor, said rotor having a side and circumferential closure, enclosing and closing air tight the space included in the rotor between the exterior of the radial pipes, the hub and said closures of the rotor, but not closing the outer ends of said radial pipes whereby all portions of the rotor outside the hub 45 except said pipes are closed against the entrance of water. 50

3. In a centrifugal pump having a stationary pressure chamber with a perforated ring between which and the inner face of the outer walls of 55 the chamber, a quantity of the liquid is held substantially without rotation and under heavy pressure, a rotor comprising in combination a circumferential ring a series of radial pipes extending from an intake, to the circumferential ring enclosing the circumference, flat side pieces at each side of said rotor secured air tight to the circumferential ring thereby forming between the side pieces and the circumferential ring enclosed air spaces. 60

4. The device as defined in claim 3, in combination with an inlet pipe and a hub on which the rotor side pieces and radial pipes are mounted, and having bearings on the inlet pipe. 65

5. The device as defined in claim 3, in combination with a driving mechanism comprising a hub on which said rotor's side pieces and radial pipes are mounted and which has bearings on which it rotates, and a pair of gear wheels one mounted on said hub and the other mounted on an inner wall of the stationary chamber. 70
